FACE FLY REPELLENT DISPENSER FOR CATTLE

Roy Goodwin, Rte. 2, Lancaster, Mo. 63548

Filed May 23, 1974, Ser. No. 473,406

Term of patent 14 years

Int. Cl. D30—99

U.S. Cl. D30—99

FIG. 1 is a perspective view of a face fly repellent dispenser for cattle showing my new design, an intermediate portion of the downwardly projecting wick being broken away and omitted to indicate indeterminate length;

FIG. 2 is an enlarged scale rear elevational view thereof;

FIG. 3 is a left-side elevational view thereof;

FIG. 4 is a front elevational view thereof;

FIG. 5 is a right-side elevational view thereof;

FIG. 6 is a top plan view thereof; and

FIG. 7 is a bottom plan view thereof.

The dash lines on FIGS. 1, 2 and 4 represent stitching.

I claim:

The ornamental design for a face fly repellent dispenser for cattle, substantially as shown and described.
